Primary Examiner — Philip S Hyder*(74) Attorney, Agent, or Firm* — MUNCY, GEISSLER,
OLDS & LOWE, P.C.(57) **CLAIM**

The ornamental design for a tool handle, as shown and described.

DESCRIPTION

FIG. 1 is a perspective view of a tool handle showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another perspective view thereof; and,

FIG. 9 is a perspective view of the tool handle in use.

The broken line portions of the tool handle form no part of the claimed design. The broken line showing of the torque wrench in FIG. 9 is provided for purposes of environment and forms no part of the claimed design.

1 Claim, 9 Drawing Sheets(56)
